UNITED STATES PATENT OFFICE.

CLARENCE T. EVANS, OF MILWAUKEE, WISCONSIN, ASSIGNOR TO THE CUTLER-HAMMER MFG. CO., OF MILWAUKEE, WISCONSIN, A CORPORATION OF WISCONSIN.

MOTOR-CONTROLLER.

1,100,964.

Specification of Letters Patent. Patented June 23, 1914.

Application filed September 9, 1912, Serial No. 719,305. Renewed November 15, 1913. Serial No. 301,257.

To all whom it may concern:

Be it known that I, CLARENCE T. EVANS, a citizen of the United States, residing at Milwaukee, in the county of Milwaukee and State of Wisconsin, have invented new and useful Improvements in Motor-Controllers, of which the following is a full, clear, concise, and exact description, reference being had to the accompanying drawing, forming 10 a part of this specification.

My invention relates to improvements in starting devices for electric motors.

More particularly it relates to compound starters, although certain features thereof 15 may be applicable to other forms of controlling devices.

Compound starters are those adapted to both start and regulate the speed of a motor. In such devices it is important to insure 20 the inclusion of the starting resistance and the exclusion of the regulating resistance prior to the closure of the motor circuit. In order to attain this result it has heretofore been proposed to provide a construction 25 whereby the starting resistance is reinserted in circuit and the regulating resistance excluded from circuit as the motor is stopped, thereby insuring the proper conditions for 30 restarting. In practice, however, it has been found that the exclusion of the regulating resistance as the motor is stopped is objectionable.

My invention has among its objects to provide a starting device which will insure 35 the inclusion of the starting resistance and the exclusion of the regulating resistance at the time of starting the motor but which will not exclude or vary the regulating resistance until after the motor has been 40 stopped.

My invention has various other objects and advantages which will be hereinafter set forth.

For the purpose of fully and clearly 45 disclosing the nature and advantages of my invention I shall describe the embodiment thereof illustrated in the accompanying drawing, it being understood that my invention is susceptible of modification.

50 In the drawing, Figure 1 is a front elevation of the device with the inclosing casing shown in section. Fig. 2 is a side eleva-

tion of Fig. 1 with the inclosing casing shown in section. Fig. 3 is a front elevation of the device, and Fig. 4 comprises a schematic view of the controlling mechanism and a diagrammatic view of one circuit arrangement therefor.

The controller includes an armature resistance regulating arm 1 and a field regulating arm 2 and an operating lever 3. As will be later more fully explained, the armature arm is biased to initial position while the field arm and starting arm are biased to move into a predetermined relation and the operating arm has an independent movement of both the armature and field arms. The construction is such that when the operating arm is moved in a direction to start the motor it moves the field arm to position to exclude all field resistance prior to moving the armature arm to remove the armature resistance. This insures the desired starting conditions. After these conditions have been established the operating arm is 75 then movable farther in the same direction to operate the armature arm to remove the armature resistance and start the motor. When all of the armature resistance is removed from circuit the armature arm is held by a retaining magnet and the operating arm is then movable in an opposite direction to move the field arm to insert field resistance to speed up the motor. When the armature arm is released by the retaining magnet the same returns to initial position thereby reinserting the armature resistance and stopping the motor while the field arm remains stationary until further operation of the operating arm. Thus no change is 80 made in the field strength of the motor during the stopping period.

The various parts of the controller are mounted upon an insulating panel 4 and inclosed in a box-like casing 5 having a removable front section 6. The two sections of the casing may be secured together by screws 7 or any other suitable means. The panel 4 is secured against shoulders 8 within the inclosing casing by means of screws 9. 100

The arms 1 and 2 are fulcrumed on a stud 10 projecting forwardly from the lower end of the base 4 and suitably secured to the base as by means of a threaded shank 11.

and nut 12. Both arms are freely rotatable on this stud. The arm 1 has a hub 13 bearing against a bearing plate 14 provided on the front side of the base 4. Surrounding the hub 13 of the arm 1 and connected thereto at one end is a coil spring 15 having its opposite end bearing against a pin 16 projecting from the base 4 through the bearing plate 14. The spring 15 biases the arm 1 to the left or in an anti-clockwise direction. The arm 2 has a hub 17 bearing against the outer face of the arm 1 while on the opposite side of the arm 2 and revolvably mounted upon the stud 10 is the pawl 18. The pawl 18 has two rearwardly extending lugs 19 and 20 arranged approximately 90 degrees apart. As best illustrated in Figs. 1 and 4, the lug 20 is of sufficient length to engage the left hand side of the armature arm 1. The lug 19 is shorter and engages only the field arm 2. The field arm 2 has an extension 21 on the right hand side of the lug 19 to be engaged thereby. A spring 22 coiled about the hub of the arm 2 has one end secured to said hub and its opposite end bearing against the left hand side of the lug 19. This spring yieldingly holds the arm 2 and pawl 18 in such a relation as to cause the lug 19 to engage the extension 21 of the arm 2. The pawl 18 is provided on its front side with diametrically disposed lugs 24 projecting into notches in an insulating disk 25. The operating arm 3 is fixed to the outer end of a stud 27 revolvably mounted in a bearing 28 in the front wall of the inclosing casing. The stud 27 passes through this wall and has fixed to its inner end a retaining collar 29. The stud 27 is in axial alinement with the stud 10 on which the arms 1 and 2 are mounted, and the collar 29 on the stud 27 has diametrically disposed lugs 30 fitting into notches in the insulating disk 25. The disk 25 thus provides an insulating coupling for rigidly connecting the operating arm 3 and the pawl 18. With this arrangement it will be observed that if the operating arm 3 is moved to the left it will operate the pawl in a counter-clockwise direction, and by engagement of the lug 19 with the lug 21 of the field arm 2 will also move said field arm in the same direction. It will further be observed that this operation does not affect the spring 17 nor the armature arm 1. On the other hand, if the operating arm be moved to the right the pawl will be moved in a clockwise direction and by engagement of the lug 19 thereof with the end of the spring 17 will tension said spring. The spring 17 allows the operating arm to be moved in the same direction independently of the field arm 2 but during said movement stores up energy for returning the arm 3 as soon as released to the normal re-

lation with the arm 2. Further, the operation of the arm 3 to the right hand and consequent clockwise movement of the pawl throws the lug 20 of the pawl into engagement with the armature arm 1, imparting a clockwise movement thereto against the action of the spring 15. The lug 20 on the pawl is preferably so disposed as to permit operation of the field arm from its extreme left hand position to its extreme right hand position before said lug engages said arm 1 and the operating arm 3 is preferably so disposed as to assume a vertical position when the field arm is in its extreme right hand position.

The armature arm carries two contact brushes 30. One engages a series of contacts 32 arranged in an arc on the panel 4 while the other engages an arc-shaped segment 33 also mounted upon the panel 4. Secured to the panel 4 on the left hand side thereof is a stop 34 for limiting the movement of the arm 1 under the influence of the spring 15. The arm 1 when against this stop disengages its brushes from the contacts 32 and segment 33. Secured to the panel 4 on the opposite side thereof is a retaining magnet 35 for holding the armature arm 1 against the action of the spring 15 in its extreme right hand position. The field arm 2 carries a contact pencil 36 movable over a series of contact buttons 37 arranged in an arc on the panel 4 and concentrically with the contacts 32.

All of the foregoing parts are mounted in front of the panel 4, thus leaving a compartment at the rear of the panel for the resistance units. In practice these units may be of any preferred type and mounted within the casing in any preferred manner. I prefer, however, to employ elongated flat units and to mount the same on the rear of the panel 4 as illustrated. As shown, there are two field resistance units 38 and 39 mounted in a parallel relation on parallel rods 40 projecting rearwardly from the base 4 and one armature resistance unit 41 mounted upon similar rods 42. The panel 4 also carries a switch arm 43 fulcrumed on a stud 44 projecting forwardly from the panel. This switch arm is adapted to engage a contact stud 45 also projecting forwardly from the panel 4. The switch arm 43 is biased into engagement with the contact stud 45 by a spring 46 coiled about the stud 44. A push button 47 extending through the top of the casing and engaging an extension 48 of the switch arm 43 provides means whereby said switch arm may be disengaged from the contact 45. This switch, as will later be set forth, is provided for deenergizing the retaining magnet 35.

The front of the casing is preferably provided with means as shown in Fig. 3 to in-

icate the manner of operation and the steps of resistance variation. As indicated by the front of the casing, the arm 3 is movable to the right to start the motor and to the left to regulate the speed of the motor.

The operation of the controller will now be described in connection with Fig. 4. In this figure the controller is shown as connected to a shunt field motor M having an 10 armature A and a shunt field winding F. An armature resistance R is diagrammatically illustrated as connected to the contact buttons 32 and a field resistance R' as connected to the contact buttons 37. The armature arm and the field arm are shown in their extreme left hand positions in which the former interrupts the motor circuit and the latter includes all field resistance. In 15 this position of the arms 1 and 2 the operating arm 3 would stand in the position shown in dotted lines, Fig. 3. Assume now that the arm 3 is moved to the right. It moves the field arm 2 in a corresponding direction through the medium of the pawl 18 and 20 spring 22 until the arm 2 reaches its extreme right hand position. When this position is 25 reached the operating arm 3 will have attained the full line position shown in Fig. 3 and the lug 20 of the pawl 18 will have been 30 brought into contact with the arm 1. Continued movement of the arm 3 to the right will accordingly move the armature arm to the right first closing the armature circuit and then cutting out the armature resistance. 35 The motor circuit is closed as soon as the armature arm engages the contact buttons 32 and segment 33. It may be traced as follows: from the positive side of the supply circuit by conductor 50 to segment 33 to and 40 through brushes 30 to contacts 32 through all of the resistance R by conductor 51 through the motor armature A by conductor 52 to the negative side of the supply circuit. The field circuit may be traced from the arm 45 1 to the arm 2 thence through the contact 36 thereof to the extreme right hand contact 37 by conductor 53 through the field winding F to conductor 52. It will thus be observed that when the motor circuit is closed all of 50 the armature resistance is included while all of the field resistance is excluded or short-circuited. Continued movement of the operating arm 3 and the armature arm 1 will gradually cut out the resistance R until all 55 of the same is excluded from circuit. When the armature arm reaches final position it is gripped by the magnet 35. The circuit of magnet 35 may be traced from the extreme left hand contact 32 by conductors 54 60 through push button switch 43 by conductors 55 through a protective resistance r by conductor 56 through said magnet by conductor 57 to conductor 52. The magnet 35 being thus connected in circuit holds the armature

arm against return movement until deenergized by failure of voltage or by the opening of the switch 43. During the movement of the operating arm past the full line position, shown in Fig. 3, the spring 22 connecting the same to the field arm is placed under 65 tension. Accordingly if after the armature arm 1 has been moved to final position the arm 3 is released it will automatically return to the full line position, shown in Fig. 3. In this position it will bring the lug 19 70 of the pawl 18 into engagement with the lug 21 on the field arm 2 whereby continued movement of the arm 3 to the left will cause the field arm to be moved in the same direction. Movement of the field arm in this direction inserts the resistance 'R' in circuit with the field winding F of the motor, thereby 75 weakening the field strength and increasing the speed of the motor. The field arm may be moved back and forth over the contacts 37 to vary the field strength at will and may be left in any desired position. Assume now that the retaining magnet 35 is deenergized, the spring 15 will at once return the armature arm to initial position, thereby 80 gradually reinserting the armature resistance R and finally opening the motor circuit. This operation, however, will have no effect upon the field arm or operating arm. Both 85 will remain in the position in which they 90 were left. Accordingly, the field strength of the motor will not be varied during the period of stopping. When, however, the armature arm reaches "off" position, thereby 95 disengaging segment 33, it disconnects the 100 field arm from circuit and thus opens the circuit of the field winding. To restart the motor it is only necessary to repeat the operation heretofore described, that is, first 105 moving the arm 3 to the right to start, and then to the left for field regulation. It makes no difference in what positions the field arm and operating arm were left during the preceding operation. Movement of 110 the operating arm in one direction will always restore the field arm to initial position and restart the motor. No backward movement whatever is necessary in order to restore the arms to the proper positions.

What I claim as new and desire to secure 115 by Letters Patent, is:

1. In a motor controller, in combination, a movable member, a second movable member, said first member being biased to return to initial position independently of said second member, and a third movable member for operating said first two mentioned members and insuring the return of said second member to initial position prior to movement of said first member away from initial 120 position.

2. In a motor controller, in combination, a movable member, a second movable mem-

- ber, said first member being biased to move to initial position independently of said second member, and a third member movable in a single direction to first return said second member to initial position and thereafter move said first member away from initial position.
3. In a motor controller, in combination, a movable member, a second movable member, said first member being biased to move to initial position independently of said second member, and a third movable member movable in one direction to first restore said second member to initial position and thereafter move said first member away from initial position and movable in a reverse direction to move said second member away from initial position independently of said first member.
- 20 4. In a motor controller, in combination, a movable member, a second movable member, said members being movable back and forth between substantially the same limits, said first member being movable toward initial position independently of said second member, and a common operating member for said first two members insuring the return of said second member to initial position prior to movement of said first member away from initial position.
5. In a motor controller, in combination, a movable member, a second movable member, said members being movable in opposite directions from their respective initial positions and said first member being movable to its initial position independently of said second member, and a common operating member for said first two members insuring the return of said second member to its initial position prior to movement of said first member away from its initial position.
6. In a motor controller, in combination, a movable member, a second movable member, said members being movable in opposite directions from their respective initial positions, and said first member being returnable to its initial position independently of said second member, and a common operating member for said first two members movable in a single direction to first restore said second member to its initial position and thereafter move said first member away from its initial position.
- 55 7. In a motor controller, in combination, a movable member, a second movable member, said members being movable in opposite directions from their respective initial positions and said first member being biased to move to initial position independently of said second member, a retaining magnet for holding said first member in a predetermined position, and a common operating member for said first two members movable in a single direction to first restore said second member to its initial position and thereafter move said first member into position to be held by said retaining magnet.
8. In a motor controller, in combination, a movable member, a second movable member, said members being movable in opposite directions from their respective initial positions and said first member being biased to move to initial position independently of said second member, a retaining magnet for holding said first member in a predetermined position, and a common operating member for said first two members movable in a single direction to first restore said second member to its initial position and thereafter move said first member into position to be held by said retaining magnet, said operating member thereupon being movable in a reverse direction to move said second member away from its initial position.
9. In a motor controller, in combination, a starting member, a speed regulating member, said starting member being adapted to automatically return to initial position independently of said speed regulating member, and a single operating member movable in one direction to first return said speed regulating arm to initial position and then move said starting member to running position.
10. In a motor controller, in combination, a starting member, a speed regulating member, and a common operating member therefor movable in a single direction to first restore said speed regulating member to initial position and then move said starting member toward running position, and movable in a reverse direction to move said speed regulating member independently of said starting member.
11. In a motor controller, in combination, a starting member, a speed regulating member, and a common operating member therefor movable in a single direction to first restore said speed regulating member to initial position and then move said starting member toward running position, and movable in a reverse direction to move said speed regulating member independently of said starting member, said speed regulating member remaining stationary upon the return of said starting member to initial position.
12. In a motor controller, in combination, a starting member, a speed regulating member, said members being movable in opposite directions from their respective initial positions, and a single operating member for said first two members insuring the return of said speed regulating member to initial position prior to starting the motor.
13. In a motor controller, in combination, a starting member, a speed regulating mem-

- ber, said members being movable in opposite directions from their respective initial positions, and a single operating member for said first two members insuring the 5 turn of said speed regulating member to initial position prior to starting the motor, said speed regulating member remaining stationary upon the return movement of said starting member to initial position.
- 10 14. In a motor controller, in combination, a starting member, and a speed regulating member, said members being movable between substantially the same limits, and said speed regulating member remaining 15 stationary upon movement of said starting member to off position, and a common operating means for said members insuring the return of said speed regulating member to initial position prior to starting the 20 motor.
15. In a motor controller, in combination, an armature resistance, a controlling member therefor, a field resistance, a controlling member therefor, said field resistance member being adapted to remain stationary upon movement of said armature resistance member to reinsert resistance, and an operating member for said armature resistance member adapted when moved in a direction to 25 cut out armature resistance to return said field resistance member to initial position prior to the removal of any of said armature resistance.
- 20 16. In a motor controller, in combination, an armature resistance, a controlling member therefor, a field resistance, a controlling member therefor, said field resistance member remaining stationary upon movement of said armature resistance member toward 30 initial position, and a single operating member movable in a single direction to first return said field resistance member to initial position and then move said armature resistance member to cut out said armature 35 resistance, said operating member being movable in a reverse direction to move said field resistance member independently of said armature resistance member to insert said field resistance.
- 35 17. In a controller for electric motors, in combination, an armature resistance, a controlling member therefor, a field resistance, a controlling member therefor, said members being movable in the same direction to remove their respective resistance, and operating means for said members insuring the removal of all of said field resistance prior to the removal of any of said armature resistance, said field resistance member remaining stationary upon movement of said 40 armature resistance member to reinsert said armature resistance.
- 45 18. In a motor controller, in combination, an armature resistance, a controlling mem-
- ber therefor, a field resistance, a controlling member therefor, said members being effective to control their respective resistances within common limits of movement and said field resistance member remaining stationary upon movement of said armature resistance member to reinsert said armature resistance, and a single operating device for both of said members insuring the removal of all of said field resistance prior to removal of any of said armature resistance. 75
19. In a motor controller, in combination, two independently movable controlling members, one of said members being biased in one direction, and a third member operatively connected to said former members and adapted when moved in one direction to move said controlling members successively in the same direction to predetermined positions, moving said biased member after said other member, said operating member 80 when moved in a reverse direction moving said latter controlling member independently of said biased member.
20. In a motor controller, in combination, two independently movable controlling members, one of the same being biased in one direction, and an operating member having a predetermined degree of movement independently of said biased member and having a resilient connection with said other controlling member whereby movement of said operating member in one direction moves said controlling members successively in the same direction to predetermined positions, the biased member being moved last, and 90 said operating member after moving said biased member being movable in an opposite direction to move said other controlling member in the opposite direction independently of said biased member. 95
21. In a motor controller, in combination, two independently movable controlling members, one adapted to control an armature resistance and the other a field resistance, means biasing said armature resistance member toward initial position, said field member being unbiased and adapted to remain in any one of a number of different positions, and an operating member having a resilient connection with said field resistance member, and a part adapted to engage said armature resistance member whereby said operating member when moved in one direction will successively move said field resistance member and said armature resistance member to first remove the field resistance and then the armature resistance, said operating member then being movable in the opposite direction to move said field resistance member to insert field resistance. 105 110
22. The combination with a motor having a shunt field winding of an armature resistance, a controlling member therefor, a

field resistance, a controlling member there-
for, and means insuring movement of said
field member to remove from circuit all of
said field resistance prior to movement of
5 said armature member to remove said arma-
ture resistance from circuit, said armature
member being movable to reinsert said ar-
mature resistance without movement of said
field member and upon reaching initial po-

sition to disconnect the motor field winding 10
from circuit.

In witness whereof, I have hereunto sub-
scribed my name in the presence of two
witnesses.
